(57) CLAIM

The ornamental design for a gun body, as shown and described.

DESCRIPTION

FIG. 1 is a front perspective view of gun body showing my new design;

FIG. 2 is a front view thereof;

FIG. 3 is a rear view thereof;

FIG. 4 is a left end view thereof;

FIG. 5 is a right end view thereof;

FIG. 6 is a top view thereof;

FIG. 7 is a bottom view thereof;

FIG. 8 is rear perspective view thereof;

FIG. 9 is another front perspective view thereof; and,

FIG. 10 is a front side view thereof assembled and in condition of use.

The broken lines in the drawings disclose unclaimed subject matter only and form no part of the claimed design.
